UNITED STATES PATENT OFFICE.

JOHN R. ROTHMAN, OF CANTON, ILLINOIS.

ADJUSTABLE DITCH-CLEANER.

SPECIFICATION forming part of Letters Patent No. 272,087, dated February 13, 1883.

Application filed November 3, 1882. (No model.)

To all whom it may concern:

Be it known that I, JOHN R. ROTHMAN, of Canton, in the county of Fulton, in the State of Illinois, have invented an Improved Adjustable Ditch-Cleaner; and I do hereby declare that the following is a full, clear, and exact description thereof, reference being had to the annexed drawing, making a part of this specification, in which like letters of reference refer to like parts, and in which the figure represents a perspective view of the same.

The object of this invention is the construction of a ditch-cleaner that by a simple and easy adjustment may be used for scraping, hoeing, shoveling, or spading.

My invention consists essentially of a metal plate or blade having two forked rods pivoted thereto, one of which is rigid to the handle and the other swiveled to a collar adjustable to different positions upon said handle, whereby said plate or blade can be held at different angles relative to the handle.

The plate or blade A of my ditch-cleaner I make with two opposite sides, A', bent up to approximately right angles with the body of it. This serves the double purpose of retaining the dirt upon it and of taking the place of ears to which to attach the forked holding-rods E and D. The end E' of the forked rod E is inserted and fastened into the end of the handle C, while the forked ends are bent into hooks and caught into the eyes or openings O O', made through the sides A' A'. The forked rod D in like manner has its forked ends bent and hooked into eyes O' O', made, as shown, through the sides A' A' of the blade A; but

the end D' of said forked rod D is bent into an eye or hook and held by the eye H of the collar F. Said collar F, being fitted to slide along the handle C, is firmly retained at any desired point thereon by means of a set-screw, G, as shown in the drawing, or by means of a wedge or cam.

To use this implement as a hoe, the collar F is slid toward the lower end of the handle C until the plate A is at almost right angles therewith. When used for shoveling, said collar is moved away from the end until said plate A is nearly parallel with the handle. A medium position like that shown in the drawing is the one at which this implement is most generally used for the purpose of ditch-cleaning.

What I claim for my patent is as follows:

1. The handle C, having forked bar E, in combination with the plate A, forked rod D, and collar F, having eye H, and a device for securing said collar at various points along said handle C, substantially as and for the purpose specified.

2. The handle C and forked rod E, in combination with the plate A, having vertical sides A' A', forked rod D, and collar F, having eye H and set-screw G, substantially as and for the purpose set forth.

In testimony that I claim the foregoing invention I have hereunto set my hand this 7th day of October, 1882.

JOHN R. ROTHMAN.
